[57] CLAIM

The ornamental design for a toy projectile, substantially as shown and described.

DESCRIPTION

FIG. 1 is a top plan view of the toy projectile showing my new design;

FIG. 2 is a side elevational view of FIG. 1;

FIG. 3 is a bottom plan view of FIG. 2;

FIG. 4 is a sectional view taken along line 4—4 of FIG. 1;

FIG. 5 is a top plan view of a modification of the toy projectile of my new design;

FIG. 6 is a side elevational view of FIG. 5;

FIG. 7 is a bottom plan view of FIG. 5; and

FIG. 8 is a sectional view taken along the line 8—8 of FIG. 5.

FIG. 1

FIG. 5

FIG. 2

FIG. 6

FIG. 3
